UNITED STATES PATENT OFFICE.

HENRY M. CRANE, OF NEW YORK, N. Y., ASSIGNOR TO GENERAL MOTORS CORPORATION, OF DETROIT, MICHIGAN, A CORPORATION OF DELAWARE.

ENGINE.

Application filed July 31, 1926. Serial No. 126,189.

This invention relates to internal combustion engines having several cylinders arranged side by side and particularly to engines of this type in which the combustion chambers extend laterally from the cylinder bores and have valve ports communicating with the laterally extending portions on the crank shaft side, cylinders of this sort being commonly known as L-head cylinders.

10 The objects of the invention are to enable engines of the type mentioned to be made shorter than is possible with the heretofore usual construction; to enable the combustion chambers to be kept cooler, and to 15 otherwise improve the construction and operation.

These objects are attained by arranging the lateral extensions of the combustion chambers and valve ports of alternate cylinders upon opposite sides of the axes of the cylinders, preferably leaving a space between the extensions of the first and third, second and fourth, third and fifth, and so on, provided there are more than two cylinders. In other words the valve port pairs of the several combustion chambers are staggered.

The accompanying drawings exemplify the invention applied to an engine with 30 eight upright cylinders in single rank adapted for motor vehicles. In said drawings, in which like reference characters indicate like parts throughout the several views,

Fig. 1 is a vertical transverse section, on plural planes, namely through the cylinder block on the line 1—1 of Fig. 3, and through the cylinder head on the line 1^a—1^a, of Fig. 2, omitting the manifolds;

Fig. 2 is a top plan view of a complete 40 engine, parts of the head having been broken away and

Fig. 3 is a top plan of an eight cylinder block showing the valve ports arranged according to this invention.

45 Referring first to Fig. 3:

Numeral 10 indicates a cylinder block having eight cylinder bores disposed side by side in a row so that all of their axes lie in a common plane. Said cylinder bores are indicated from front to rear by numerals 11, 12, 13, 14, 15, 16, 17 and 18, respectively. The block illustrated forms part of a four stroke cycle engine in which the combustion chambers extend laterally from the cylinder bore, within the head, and the inlets for

combustible mixture and outlets for burnt gases are controlled by poppet valves that open and close, in proper sequence, ports formed through the block into the chambers at one side of the cylinder bores. The ports of alternate cylinders are disposed on opposite sides of the block as indicated in the drawing. In the illustrated embodiment, considering cylinder 11 as being in the front end of the block, and looking from front to rear, the ports of cylinders 11, 13, 15 and 17 are on the left hand side of the block, while the ports of cylinders 12, 14, 16 and 18 are on the right hand side. The intake ports on the left hand side are indicated by the reference characters I¹¹, I¹³, I¹⁵ and I¹⁷; the exhaust ports by E¹¹, E¹³, E¹⁵ and E¹⁷. On the right hand side of the inlets ports are indicated by reference characters I¹², I¹⁴, I¹⁶ and I¹⁸, the exhaust ports by E¹², E¹⁴, E¹⁶ and E¹⁸. By preference air gaps 20 intervene on each side between laterally projecting portions of the engine block and head that contain the valve ports and communicating combustion spaces.

An engine having the arrangement of combustion chambers and valve ports exemplified in Fig. 3, may have an intake and exhaust manifold on each side and a cam shaft on each side to operate the valves.

In Fig. 1 the left hand cam shaft (looking from front to rear) is indicated by numeral 21, the right hand cam shaft by numeral 22. These cam shafts are equipped with the usual valve lifting cams 23, to be rotated at half crank shaft speed by the usual gearing (not shown) driven by the crank shaft disposed within the casing 24 (Fig. 2). The individual valves and valve operating devices are no part of this invention and they may be of any standard type used in L-head engines. Fig. 1 shows the crank case 25 supporting the block 10 and housing the crank shaft 26 and cam shafts 21 and 22. Beneath the crank case is the usual oil pan 27. Alternately disposed on opposite sides of the block are lateral projecting parts or overhangs 28 and 29 in which the inlet and exhaust passages are formed. An inlet passage is shown at 30 in Fig. 1. The inlet poppet valve 31 may be considered as controlling the admission of fuel mixture through the passage 30 and port I¹⁷ to the combustion chamber of cylinder 17. Valve 31 has a stem 32 slidable in

a bearing 33 formed in the overhang 29; the lower end of stem 32 rests upon a tappet 34, guided in a bearing 35 on the crank case and the tappet engages the cam 23; spring 36 keeps the tappet in contact with the cam, all according to usual practice. The air spaces between the overhangs 29 and the crank case are covered by removable plates 37 in the same manner as it is customary to cover in and house the valve stem spaces on one side of the usual L-head engine. The other valves on both sides, both inlet and exhaust, are of similar construction and are similarly operated. The overhangs 28 are spaced from each other by the air gaps 20, previously referred to, and the overhangs 29 are likewise so spaced.

Fig. 2 shows an intake manifold 38 on the right hand side of the engine, another indicated by 39 on the left hand side. The right hand exhaust manifold is shown at 40 and the left hand one at 41. These manifolds have ports registering with the respective passages that communicate with the valve ports shown and identified in Fig. 3. For purposes of equal cooling of the several chambers it is deemed advisable to have an intake port on one side and an exhaust port on the other of each air gap.

The head casting 42 may be bolted to the cylinder block. In it are formed the several combustion chambers 43, alternating in position as described. It may have gaps in its opposite edges, staggered with respect to each other, as shown in Fig. 2 and registering with the air gaps 20. The individual combustion chambers are, in contour, typical of those in L-head engines used in motor vehicles. In plan view each is somewhat triangular in outline, with the base of the triangle registering with the overhang of the cylinder block. The valve ports lie side by side within the base portion and the cylinder bore registers with the space within the apex. The chambers, as shown in Fig. 1, have more clearance over the valve ports than over the cylinder bores; as shown in Figs. 2 and 3, they are considerably wider over the valve ports than over the cylinder bore. It will be seen that a plane perpendicular to the crank shaft axis midway between adjacent cylinders will intersect the combustion chambers of the adjacent cylinders. Adjacent combustion chambers overlap, in other words. Ignition plugs 44 may be placed in the best firing position. In the drawings they are shown adjacent the valve ports substantially in the midvertical transverse plane of the chambers.

The utilities of the construction and arrangement described and illustrated may be readily apprehended. L-head engines have a certain advantage over other types in that the valve mechanism is simple, because the valve stems can be directly operated by the

cam shaft without the intervention of levers; but the combustion chambers necessarily have a more extensive plan area than those of the "overhead" valved type. In order to get sufficient area and lift of valves to attain high speed the valve ports must be relatively large. As the valve ports lie side by side, the chamber must be wide,—measured longitudinally of the engine,—always, in high speed engines, wider than the diameter of the cylinder bore. In consequence the length of multi-cylinder L-head engines of high speed now in general use is determined by the width of the chambers at the valve ports rather than by the diameter of the cylinder bore.

By adopting the arrangement of this invention the length of the engine may be governed by the diameter of the cylinder bores. Thus, multiple cylinder engines of this type may be made shorter than heretofore with consequent saving of space, lightening of weight, shortening and stiffening the crank shaft and reducing costs. In motor cars with eight cylinders in one rank, for example, the saving of space within the hood, the lesser dead weight, and the minimizing of torsional vibrations incident to the described arrangement are considerations of very great importance.

The described arrangement also permits the presence of air gaps as described adjacent the exhaust valves, thus facilitating cooling and tending to prevent such high temperatures as to cause knocking or detonation,—a phenomenon commonly associated with excessively high temperatures and pressures in the combustion chambers.

While one specific embodiment of the invention has been described and illustrated in accordance with the provisions of the patent statutes, the invention is not intended to be limited to said specific embodiment as other forms may be designed within the principles of the invention.

What I claim is:

- An engine comprising L-head cylinders arranged side by side, the valve ports of adjacent cylinders being disposed on opposite sides of the cylinder axes.
- An engine comprising L-head cylinders arranged side by side, with laterally extending combustion chambers having valve ports located side by side in the laterally extending portions of the chambers; the laterally extending portions and valve ports appertaining to adjacent cylinders being disposed on opposite sides of the cylinder axes.
- An engine comprising L-head cylinders arranged side by side, with laterally extending combustion chambers having valve ports located side by side in the laterally extending portions of the chambers; the laterally extending portions and valve ports apper-

taining to adjacent cylinders being disposed on opposite sides of the cylinder axes, and the extensions of the chambers of adjacent cylinders being intersected by a transverse plane midway between the axes of said cylinders and perpendicular to the crank shaft.

4. A cylinder block having L-head cylinders arranged side by side with valve ports therein at one side of each cylinder, the valve ports appertaining to adjacent cylinders being disposed on opposite sides of the cylinder axis.

5. An engine comprising L-head cylinders arranged side by side, the valve ports of adjacent cylinders being disposed on opposite sides of the cylinder axes, and separated from the adjacent ports in the same side by an air gap.

6. A cylinder block having L-head cylin-

ders arranged side by side and lateral projecting portions each having inlet and exhaust ports for one cylinder, said projecting portions being alternately disposed on opposite sides of the block, adjacent projections on each side being separated by an air gap.

7. An engine comprising L-head cylinders having their axes lying substantially in a common plane with laterally extending combustion chambers provided with valve ports in the laterally extending portions; the laterally extending portions of the chambers and the valve ports appertaining to adjacent cylinders being disposed on opposite sides of said common plane.

In testimony whereof I affix my signature.

HENRY M. CRANE.
